(57) **CLAIM**

The ornamental design for a translucent pill crusher pouch with angled seal, as shown and described.

DESCRIPTION

FIG. 1 is a perspective view of a translucent pill crusher pouch with angled seal showing my new design;

FIG. 2 is a front elevational view thereof, the other side being a mirror image;

FIG. 3 is a bottom plan view thereof;

FIG. 4 is a top plan view thereof;

FIG. 5 is a left side elevational view thereof; and,

FIG. 6 is a right side elevational view thereof.
